(57) **CLAIM**

The ornamental design for a plumbing fixture support, as shown and described.

DESCRIPTION

FIG. 1 is a left, top, front perspective view of a plumbing fixture support embodying our new design;

FIG. 2 is a front elevational view thereof;

FIG. 3 is a left side elevational view thereof, the right side elevational view thereof being a mirror image of the left side shown;

FIG. 4 is a rear elevational view thereof;

FIG. 5 is a top plan view thereof; and,

FIG. 6 is a bottom plan view thereof.

The broken line representations in the figures are for the purpose of illustration only, and form no part of the claimed design.

In a preferred embodiment, the nature of this product is a support for a plumbing fixture, such as a support table for a lavatory.
